UNITED STATES PATENT OFFICE.

DUDLEY OGDEN SAYRE, OF SOUTH ORANGE, NEW JERSEY.

SPRING-HOLDER FOR GAS-GLOBES.

SPECIFICATION forming part of Letters Patent No. 621,948, dated March 28, 1899.

Application filed December 15, 1898. Serial No. 699,516. (No model.)

To all whom it may concern:

Be it known that I, DUDLEY OGDEN SAYRE, a citizen of the United States, residing at South Orange, county of Essex, State of New Jersey, have invented certain new and useful Improvements in Spring-Holders for Gas-Globes, fully described and represented in the following specification and the accompanying drawings, forming a part of the same.

The object of the present invention is to simplify the construction and operation of the springs which are used upon gas-globe holders and to wholly conceal the springs within the periphery of the holder. Such holders are provided with a ring upon which the flange of the globe rests by its lower edge to sustain the weight of the globe and with a peripheral rim within which such flange is inserted and which operates in practice to conceal it from view. Such globe-flange is always flared outwardly at its base, and I provide an exceedingly simple means of securing the flange automatically within the rim by reflexing a spring-leaf from the outer margin of the rim inwardly toward the supporting-ring at an acute angle with the axis of the holder and forming the end of such spring-leaf to engage the exterior of the globe-flange adjacent to its supporting edge. When the globe-flange is applied to the holder, it presses upon the inclined inner surfaces of the springs and presses them outward automatically until its edge has passed the projecting point of the spring, when they react upon its sloping surface and lock it in the holder. The flared exterior of the flange is thus held securely in place, while the sloping surface of the flange enables it in many cases to push back the point of the spring-leaf when it is necessary to lift the globe from the holder. The projection of the springs inwardly from the outer margin of the globe-holder rim distinguishes them from the springs which are commonly projected outward upon globe and chimney holders to embrace the flange of the globe or chimney, as my springs are concealed within the holder.

The invention will be understood by reference to the annexed drawings, in which—
Figure 1 is a plan of an annular globe-holder. Fig. 2 is a vertical section of the same with a

portion of the globe. Fig. 3 is a view upon the outer side of one of the springs shown in Fig. 1. Fig. 4 is a diagram of the blank to form such a spring. Fig. 5 shows the edge 55 of the globe-holder and globe with a spring formed integrally upon the globe-holder. Fig. 6 is a section of the globe-holder with the left side broken away, showing one of the integral springs. Fig. 7 is a perspective view 60 of a spring, showing an alternative construction for the foot. Fig. 8 shows a part of the globe-holder rim (upon its inner side) with a spring secured thereto by small lugs. Fig. 9 is a plan in section on line 9 9 in Fig. 8. 65

A designates the rim of the holder, and A' the ring which supports the flange of the globe. The ring is shown provided with the usual arms, connected with an eye A³ in the center for attachment to the gas-fixture. 70

Three spring-tongues are shown in Fig. 1 riveted to the rim A and extended first upwardly and then downwardly toward the ring A'. The tongue is formed in one piece of spring metal, as shown in Fig. 4, and is bent, 75 as shown in Fig. 2, into three parts—a foot b, a flexible leaf B, and an inclined lip B'. The leaves B are sloped inwardly and are proportioned to press elastically upon the flange C of the globe D, which, as is common in such 80 constructions, is outwardly flared from the globe. The lip B' upon each spring is sloped outwardly like the flange C. The lower edge of the flange when inserted within the sloping sides of the leaves B and pressed downwardly 85 operates to force them out until the bottom edge of the flange passes the junction of the leaves B and lips B', and when the flange makes contact with the ring A', as shown in Fig. 2, the leaves are moved inward sufficiently for the lips B' to engage the outer flaring surface of the flange and hold the same within the rim A by elastic pressure. The sloping surfaces of the lips afford a seat upon which the flange presses when it is lifted from 90 the globe and serve to force the leaves B outwardly until the flange is drawn clear of the springs. Three of the springs are shown in Fig. 1, which are in practice made of suitable strength and elasticity for holding the 95 globe securely from displacement by accidental jars. In practice the flange of the 100

globe is inserted under two of the springs when applying the globe to the holder and then pressed downwardly upon the remaining spring, which yields until the flange is fitted 5 completely with the holder, as shown in Fig. 2.

The construction shown in Figs. 1 and 2 is especially adapted for the conversion of ordinary globe-holders, of which large numbers are in use, provided with screws to grasp the 10 globe-flange, as such screws may be readily removed and the spring-leaves riveted to the rim A, thus providing the holder with an automatic clamp for the globe.

In the manufacture of new globe-holders 15 the springs may be formed integral with the rim A, which obviously necessitates the use of a larger piece of sheet metal to form the holder. To use as small a piece of sheet metal as possible, the springs may in such case 20 be formed without the lips B', as the ordinary globe-flange is suitably inclined to press the spring outwardly without the use of such lip. Figs. 5 and 6 show such a construction for the spring. In this construction the 25 spring-leaf is formed as a tongue projected upwardly, as represented by the dotted lines b' in Fig. 6, and then bent downwardly and sloped inwardly, as shown in Fig. 5, terminating a sufficient distance above the ring A' to 30 press within the neck of the flange C. Such tongues yield the same as those shown in Fig. 2 when the flange C is pressed downwardly into the holder; but as the free end of the 35 leaf is unprovided with the lip B' the release of the flange from the spring requires an inclination upon the flange, which makes it capable of slipping past the point of the spring when lifted. Where the flange is not formed with a suitable inclination, it may not be dislodged from the springs by merely lifting the 40 globe, but requires in such case means for retracting one of the springs to release the flange. To free the spring from the flange, a stud e may be projected from the spring 45 outwardly through the rim A to draw one of the springs outwardly when lifting the globe from the holder.

It is obvious that the integral spring may be formed with the lip B', the same as is 50 shown in Fig. 2, and the necessity of a stud be wholly avoided.

The separate spring is shown in the drawings riveted to the ring A in the rear of the leaf B, which necessitates the riveting of the 55 spring to the ring before the leaf is bent into its working position; but the spring may be made with a foot of greater width than the leaf, as indicated in Fig. 7, so that rivets may be inserted through the two sides of the foot 60 after the spring is completely bent.

The invention, as shown in Fig. 2, permits the globe to be applied to and removed from the holder instantly and without operating any of the clamping devices by the fingers.

65 Figs. 8 and 9 illustrate a modification of the means that may be used to secure the spring upon the globe-holder, the spring being shown

in Fig. 8 in vertical section at the top to expose the foot-piece only, which is represented with a notch c in each side, as may be formed by cutting the blank where indicated by dotted lines c in Fig. 4. Fig. 9 shows a portion of the rim of the holder, in section on line 9 9 in Fig. 8, intersecting the foot-piece b through the notches and showing lugs a bent inwardly 75 from the rim at a suitable distance to fit the notches and adapted to be clenched down upon the front side of the foot. The lower lug is shown thus clenched and the upper one in the position in which it would be bent 80 when the spring is applied to the rim. The spring may, if desired, be made of wire instead of sheet metal and bent to correspond with the form of the leaf B and lug B' and provided with a foot of suitable character to 85 attach to the globe-holder by rivets or lugs.

I am aware that springs have been attached to gas-globe holders for securing the globe-flange therein; but my invention differs from those previously used in having the spring-leaf projected inwardly from the outer edge 90 of the peripheral rim A, by which it bends from a point adjacent to the edge of such rim, and its flexibility increases from such edge toward its inner point, which presses upon 95 the globe-holder. By this construction a very short spring can be secured by a single foot to the globe-holder and projected within the rim A, where it is wholly concealed.

With a globe-flange of the ordinary inclination, as is shown in Fig. 2, the spring serves 100 to admit and release the flange automatically, the addition of the inclined lip B' facilitating the admission and release of the flange in case it has an excessive outward flare.

Having thus set forth the nature of the invention, what is claimed herein is—

1. The globe-holder having the ring A' with central eye for supporting it upon the gas-fixture as usual, and the peripheral rim A to 110 inclose the globe-flange, such rim having a series of springs reflexed inwardly from the outer margin of such rim toward the ring A' at an acute angle with the axis of the holder to conceal them within its rim, and adapted 115 to engage a flaring globe-flange, substantially as herein set forth.

2. The globe-holder having the ring A' with central eye for supporting it upon the gas-fixture as usual, and the peripheral rim A to 120 inclose the globe-flange, such rim having a series of springs reflexed inwardly from the outer margin of such rim toward the ring A' at an acute angle with the axis of the holder to conceal them within its rim, and the most 125 projecting point of such spring being formed to engage the exterior of the globe-flange adjacent to its supporting edge, substantially as herein set forth.

3. The globe-holder having the ring A' with central eye for supporting it upon the gas-fixture, as usual, and the peripheral rim A to 130 inclose the globe-flange, such rim having a series of springs reflexed inwardly from the

outer margin of such rim toward the ring A' at an acute angle with the axis of the holder to conceal them within its rim, and provided at their lower ends each with the outwardly-inclined lip B', and the springs thus adapted to admit and release the globe-flange automatically, substantially as herein set forth.

In testimony whereof I have hereunto set my hand in the presence of two subscribing witnesses.

DUDLEY OGDEN SAYRE.
